DECANTER

Arnold I. Lorenzen, Toledo, Ohio, assignor to
Hiram Walker & Sons, Inc., Peoria, Ill.

Application October 26, 1953, Serial No. 27,317

Term of patent 7 years

(Cl. D58-6)

To all whom it may concern:

Be it known that I, Arnold I. Lorenzen, a citizen of the United States, residing at Toledo, State of Ohio, have invented a new, original, and ornamental Design for Decanter, of which the following is a specification, reference being had to the accompanying drawing, forming a part hereof.

Fig. 1 is a front elevational view of a decanter, showing my new design;

Fig. 2 is a rear elevational view thereof;

Fig. 3 is a side elevational view thereof; and

Fig. 4 is a vertical cross-sectional view thereof, taken on the line 4—4 of Fig. 2.

I claim:

The ornamental design for a decanter, as shown.
